AXEL OLOF ENGBERG, OF STOCKHOLM, SWEDEN, AND ERIK BILDE, OF BERLIN-TEMPELHOF, GERMANY, ASSIGNEES, BY MESNE ASSIGNMENTS, TO ELECTROLUX CORPORATION, A CORPORATION OF DELAWARE

SUCTION CLEANER NOZZLE

Application filed April 28, 1927, Serial No. 186,740, and in Germany September 8, 1926.

Our invention relates to vacuum cleaner nozzle apparatus and more particularly to nozzle apparatus of the type having a plurality of nozzle openings for different kinds or degrees of suction.

The object of the invention is to provide nozzle apparatus having main and auxiliary nozzle openings constructed so that, by a simple relative movement of parts, selectivity of suction with respect to nozzle openings may be readily obtained.

The nature of the invention will become apparent from a consideration of the following description taken in conjunction with the accompanying drawings forming a part of this specification, of which:

Fig. 1 shows a vacuum cleaner comprising nozzle apparatus in accordance with the invention;

20 Fig. 2 shows a detail of the apparatus of Fig. 1;

Fig. 3 shows the apparatus of Fig. 1 with a different relative position of parts;

25 Fig. 3a shows a detail of an alternative locking means;

Fig. 4 is an end view of the apparatus of Fig. 1;

Fig. 5 shows one position of parts of another embodiment of the invention;

30 Fig. 6 shows a different relative position of parts of the structure of Fig. 5;

Fig. 7 is a perspective view of the end of a tubular member forming part of the apparatus of certain embodiments;

35 Fig. 8 shows still another embodiment of the invention with the parts in one position; and

Fig. 9 shows the structure of Fig. 8 with the parts in another position.

40 Referring to Figs. 1, 2, 3, and 4, the apparatus comprises a nozzle body 10 which may be in the form of a cast body, made, for instance, of cast aluminum. The nozzle body has an upper cylindrical portion 11 and a lower flared portion 12. At the bottom of the flared portion 12 is the main nozzle opening 13. This nozzle opening is a relatively narrow, transversely elongated opening, the width thereof being shown in Figs. 1 and 3 and the transverse extent being shown in

Fig. 4. The nozzle body has an internal bore 14. This bore extends across the downwardly directed channel 15 leading to opening 13 and through the end wall 16 of the nozzle body. This provides an opening 17 in this end wall, which we will term the auxiliary opening of the nozzle body.

The inner part of the cylindrical portion 11 is of greater diameter than the bore 14. A cap member or nut 18 is screwed onto the upper end of the cylindrical portion 11 of the nozzle body. This cap member has a central opening 19.

A tubular member 20 is positioned in the nozzle body. Tubular member 20 is of an external diameter substantially equal to the diameter of bore 14. This tubular member is positioned in the passage of the nozzle body 10 formed by the interior of the cylindrical portion 11, the bore 14 and the opening 19 in member 18. An annular space 21 is formed between the outer surface of tubular member 20 and the inner surface of the cylindrical portion 11.

Secured to tubular member 20 is a guide ring 22. Ring 22 carries a projecting stop or guide pin 23, which may be in the form of a screw. The tubular member 20 is longitudinally slidable in the cylindrical portion of the nozzle body. Ring 22 moves with the tubular member 20 and in the annular space 21. The stop 23 moves in a longitudinal slot 24 cut in the inside surface of cylindrical portion 11. Adjacent the ends of slot 24 are cross-slots 25 at right angles thereto adapted to receive stop 23.

A spring 26 is fastened at one end 27 to ring 22 and at the other end 28 to the nozzle body. Spring 26 is under torsion so that it will move stop 23 into cross-slots 25 when tubular member 20 is in such position as to permit this. It also exerts a force longitudinally of the tubular member, urging it toward the position shown in Fig. 1. A packing ring 29 is inserted between cap member 18 and the cylindrical portion of the nozzle body to prevent leakage of air into the nozzle apparatus at this point.

Tubular member 20 has one of two positions in the nozzle body. Fig. 1 shows what

we term a retracted position. Fig. 3 shows what we term an advanced position. In the retracted position, shown in Fig. 1, a cover or flap lid 30 covers opening 17. Suitable means is provided to urge cover 30 into closed position over opening 17 as by a spring hinge 31. The parts are finished so that there is a tight fit between cover 30 and the portion of the nozzle body adjacent opening 17 when the cover is closed.

In the advanced position, shown in Fig. 3, the end of tubular member 20 projects through opening 17 and holds cover 30 open. In this position the side of tubular member 15 20 at 32 closes the flared passageway 15. In this position the end opening 33 of the tubular member which is formed at an angle to the axis thereof, as shown, constitutes the auxiliary nozzle opening of the nozzle apparatus as a whole.

Tubular member 20 is connected to a flexible hose member 34, in turn connected to the suction inlet of a vacuum cleaner housing 35 enclosing the usual suction-producing mechanism.

When the main nozzle opening is to be used for suction, the tubular member 20 is in the retracted position shown in Fig. 1. Cover 30 then covers opening 17 so that air can be sucked in only through the main nozzle opening 13. In this position of the parts, stop 23 is in the upper cross-slot 25 and is urged thereinto by the spring 26. Suppose that the apparatus is being used in this position for cleaning a carpet. Suppose that there is a thread, or, for example, a relatively heavy object, on the carpet, which is not removed by the suction through opening 13. To obtain greater suction, the parts are shifted to the advanced position shown in Fig. 3 so that the auxiliary nozzle opening 33 with its greater suction effect may be used for picking up the thread or object. To change the position, the parts are first twisted relatively to each other so that stop 23 leaves cross-slot 25. The parts are then moved longitudinally relative to each other against the tension of spring 26 and stop 23 moves in groove 24 until the lower cross-slot 25 is reached, when the spring 26 urges the stop into this cross-slot. The parts are then locked in the advanced position shown in Fig. 3.

It will be seen that the main nozzle opening is cut off by the tubular member when the auxiliary nozzle opening is used. When the auxiliary nozzle opening is not needed any more, the parts are again twisted to remove stop 23 from the lower cross-slot 25 and the parts are then permitted to move longitudinally until stop 23 engages the upper cross-slot 25, the parts then being locked in the position shown in Fig. 1.

Fig. 3a shows an alternative means for locking member 20 in given position. This

means includes a lock-shot 36, spring pressed by a spring 37 and cooperating with a recess 38 in tubular member 20.

In Figs. 5 to 9, the same reference characters are used as those for corresponding parts in Figs. 1 to 4.

In the embodiment shown in Figs. 5, 6, and 7, the auxiliary nozzle opening is formed by the end opening of tubular member 20 in cooperation with the cover 30. The end opening of tubular member 20 is formed, as shown in Fig. 7, by cutting the tubular member transversely at 40 and obliquely at 41. The inside surface of the cover 30 is flat and cooperates with the surface 41 in advanced position to restrict the size of the auxiliary nozzle opening to the part limited by the surface 40 and the part of the cover adjacent surface 40. In other words, in this embodiment, cover 30 cuts off the end opening of tubular member 20 so far as corresponds to surface 41. In the apparatus illustrated it will be seen that this reduces the auxiliary opening 33 to approximately one-half of the internal transverse area of tubular member 20. In this embodiment also, the side surface of tubular member 20 at 32 cuts off the main nozzle opening 13 in advanced position. It will be seen that by this means the auxiliary nozzle opening can be reduced so that a great suction velocity is obtained. Otherwise than this difference, the embodiment of these Figs. 5 and 6 is similar to that of the previously described figures.

The embodiment shown in Fig. 8 also differs merely in the formation of the auxiliary nozzle opening, which in this embodiment is designated by reference character 42. Opening 42 is a fixed opening in the nozzle body 10 immediately in front of the main nozzle opening 13. The front wall 43 of the nozzle body is integral with the nozzle body proper, and between this wall and channel 15 is a web 44 in which is an opening 45. The tubular member 20 is formed as shown in Fig. 7. In the advanced position shown in Fig. 8, the surface 41 of the tubular member 20 abuts against the wall 43. The surface 40 engages in the opening 45. Passage is provided for auxiliary suction through opening 42 and through that part of the end opening of tubular member 20 which is bounded by the surface 40. Again in this embodiment the side wall of tubular member 20, at 32, cuts off suction through the main nozzle opening when the tubular member is in advanced position as shown in Fig. 8 and auxiliary suction is being used. When the tubular member 20, in this embodiment, is pulled back to retracted position, the whole end opening of tubular member 20 is made available for suction and the suction in this case is both through the main nozzle opening 13 and the auxiliary nozzle opening 42. For picking up a thread or the like from a

carpet, the parts are moved to the position shown in Fig. 8, which provides a very strong suction through the auxiliary nozzle opening 42. While we have shown both the slot arrangement and the lock-shot arrangement for determining the relative position of parts, it will be understood that these may be used alternatively.

It will be seen that in each of the embodiments, the side of the tubular member 20 and the inside of the nozzle body are formed to provide a valve for cutting off suction through the main nozzle opening when the tubular member is in advanced position.

It will be understood that variations in structure may be made within the spirit and scope of the invention as defined in the appended claims.

We claim:

1. In a vacuum cleaner, a nozzle body having a main nozzle opening and an auxiliary nozzle opening therein, and a tubular member longitudinally movable in said nozzle body to communicate one or both of said nozzle openings with the suction of the vacuum cleaner.

2. In a vacuum cleaner, a nozzle body having a main nozzle opening and an auxiliary nozzle opening therein, a tubular member 30 slideable in said nozzle body and communicating with the suction of the vacuum cleaner, said tubular member having an opening therein to communicate said member with said nozzle openings, and means positioning said tubular member in said nozzle body to communicate with one or both of said nozzle openings.

3. In a vacuum cleaner, a nozzle body having a main nozzle opening and an auxiliary nozzle opening therein, a tubular member 40 slideable in said nozzle body and communicating with the suction of the vacuum cleaner, said tubular member having an opening for communication with said nozzle openings, and means positioning said tubular member 45 in said nozzle body to communicate with one or both of said nozzle openings, said positioning means including a longitudinal slot in said nozzle body and a cooperating guide pin in said tubular member.

4. In a vacuum cleaner, a nozzle body having a main nozzle opening and an auxiliary nozzle opening therein, a tubular member 55 slideable in said nozzle body and communicating with the suction of the vacuum cleaner, said tubular member having an opening for communication with said nozzle openings, and means positioning said tubular member 60 in said nozzle body to communicate with one or both of said nozzle openings, said positioning means including a longitudinal slot in said nozzle body, cross-slots at the ends of said longitudinal slot and a cooperating guide pin in said tubular member.

5. In a vacuum cleaner, a nozzle body having a main nozzle opening and an auxiliary nozzle opening therein, a tubular member 70 slideable in said nozzle body and communicating with the suction of the vacuum cleaner, said tubular member having an opening for communication with said nozzle openings, and means positioning said tubular member in said nozzle body to communicate with one or both of said nozzle openings, 75 said positioning means including a longitudinal slot in said nozzle body, cross-slots at the ends of said longitudinal slot, a cooperating stop member in said tubular member, and means normally urging said tubular member to one end of said longitudinal slot, said last mentioned means exerting a torsional force on said tubular member to move said stop member into said cross-slots for locking the tubular member in its limiting 85 positions.

6. In a vacuum cleaner, a nozzle body having a main nozzle opening and an auxiliary nozzle opening therein, a tubular member 90 slideable in said nozzle body and communicating with the suction of the vacuum cleaner and having an opening therein for communicating with the nozzle openings, and spring pressed locking means positioning said tubular member in said nozzle body to 95 communicate with one or both nozzle openings as desired.

7. In a vacuum cleaner, a nozzle body having a main opening and an auxiliary opening therein and having a cylindrical portion, 100 a tubular member longitudinally slideable in said cylindrical portion, and means for positioning said tubular member in said cylindrical portion in either an advanced position or a retracted position, the side of said 105 tubular member and the inside of said nozzle body comprising a valve for cutting off suction through said main opening, and said tubular member being formed to permit suction through said auxiliary opening in advanced position and to permit suction through said main opening in retracted position.

8. In a vacuum cleaner, a nozzle body having a plurality of openings therein and having a cylindrical portion, a tubular member longitudinally slideable in said cylindrical portion, and means for positioning said tubular member in said cylindrical portion in either of two positions, said tubular member 120 cooperating with one of said openings to permit suction and the side thereof together with the inside of said nozzle body comprising a valve for cutting off suction through the other opening in one of said positions, and said tubular member permitting suction through said other opening in the other of said positions.

9. In a vacuum cleaner, a nozzle body having a main opening and an auxiliary opening 125

- therein and having a cylindrical portion, a tubular member longitudinally slideable in said cylindrical portion, and spring-pressed means for positioning said tubular member in said cylindrical portion in either an advanced position or a retracted position, the side of said tubular member and the inside of said nozzle body comprising a valve for cutting off suction through said main opening, and said tubular member being formed to permit suction through said auxiliary opening in advanced position and to permit suction through said main opening in retracted position.
15. In a vacuum cleaner, a nozzle body having a plurality of openings therein and having a cylindrical portion, a tubular member longitudinally slideable in said cylindrical portion, and spring-pressed means for positioning said tubular member in said cylindrical portion in either of two positions, said tubular member cooperating with one of said openings to permit suction and the side thereof together with the inside of said nozzle body comprising a valve for cutting off suction through the other opening in one of said positions, and said tubular member permitting suction through said other opening in the other of said positions.
20. 11. In a vacuum cleaner, a nozzle body having a plurality of openings therein and having a cylindrical portion, a tubular member slideable in said cylindrical portion, and means for positioning said tubular member in said cylindrical portion in either of two positions, said tubular member cooperating with one of said openings to permit suction and the side thereof together with the inside of said nozzle body comprising a valve for cutting off suction through the other opening in one of said positions, and said tubular member permitting suction through said other opening in the other of said positions.
25. 12. In a mouth piece for a vacuum cleaner, a nozzle, a nozzle member movable relatively to said nozzle for controlling communication of said nozzle with the suction means of said cleaner, a longitudinal guide slot in said nozzle having cross slots at the ends thereof, said nozzle member having a stop sliding in said slots, and means normally urging said nozzle member to one end of said longitudinal slot, said means also exerting a torsional force on said nozzle member to move said stop into said cross slots for locking the nozzle member in either of its limiting positions.
30. 13. Suction cleaner nozzle apparatus comprising a nozzle member formed with a first passageway therethrough, a projection on said member having a second passageway therethrough and forming a main suction nozzle, said second passageway communicating with said first passageway, said member being formed with an auxiliary nozzle opening in line with said first passageway, means for closing said auxiliary nozzle opening, a tubular member slidably mounted in said first passageway and having an open end, means for positioning said tubular member so that the open end thereof extends through said auxiliary nozzle opening, and means for positioning said tubular member so that said open end is within said nozzle member, said second passageway communicating with said first passageway at a point between said auxiliary nozzle opening and the open end of said tubular member when the latter is in the last mentioned position.
35. 14. Suction cleaner nozzle apparatus comprising a nozzle member formed with a first passageway therethrough, a projection on said member having a second passageway therethrough and forming a main suction nozzle, said second passageway communicating with said first passageway, said member being formed with an auxiliary nozzle opening in line with said first passageway, a hinged spring pressed member for normally closing said auxiliary nozzle opening, a tubular member slidably mounted in said first passageway and having an open end, means for positioning said tubular member so that the open end thereof extends through said auxiliary nozzle opening, and means for positioning said tubular member so that said open end is within said nozzle member, said second passageway communicating with said first passageway at a point between said auxiliary nozzle opening and the open end of said tubular member when the latter is in the last mentioned position.
40. In testimony whereof we hereunto affix our signatures.
